POCKET FLASHLIGHT

Eugene H. Phillips, Glendale, Calif., assignor to
Lennan Lights, Inc., Burbank, Calif.

Application August 2, 1946, Serial No. 687,917

9 Claims. (Cl. 240—10.68)

1

The present invention relates generally to switching means for electric lights and more particularly to flashlights in which the switch mechanism is incorporated with means for supporting the light bulb.

Many attempts have been made in the past to design a pocket light of the type commonly referred to as a "pen" light which was simple enough in its operation and construction to be inexpensive to manufacture, and rugged enough to operate over long periods of time without requiring repair or replacement of parts. It is essential in lights of this general type that they be very inexpensive and hence have a minimum number of working parts. Furthermore, the nature of the parts themselves must be such that they lend themselves to economical quantity manufacture.

While pocket flashlights meeting some of these requirements have been manufactured and sold, they have had certain disadvantages. Among these disadvantages, one frequently encountered is that which arises from the fact that the switching mechanism for turning the light on and off is difficult to operate in the dark and not infrequently fails to maintain a secure electrical contact at the switch points.

It is then, a major object of my invention to provide a pocket flashlight of the class described requiring only a single simple pressure operation to either turn on or extinguish the light.

Another object of my invention is to provide a light of the class described in which the electrical contact of the switch point is maintained by spring pressure during the time that the light is "on" thus assuring definite electrical contact.

It is a further object of my invention to provide a light having a minimum number of working parts all of which are capable of economical mass production and which parts are rugged and simple.

The foregoing and other objects and advantages of my invention will appear from a consideration of the following description and attached drawings of a pocket light embodying the invention.

Briefly described my invention makes use of the center base terminal of a conventional flashlight bulb as one of the contact points of a make-break switch. The other of the two contacts required for such a switch is, in the device embodying my invention, the top center terminal of a conventional "pen-light" battery cell. Contact is made between these two switch points by pressing the bulb inwardly against spring pressure

2

and into contact with the battery. The bulb is held in this "on" position by means of a novel annular detent member which will be described in more detail hereinafter. The light is further designed to be extinguished by releasing the detent through the action of a slideable sleeve surrounding the bulb and projecting forwardly therewith.

For a more detailed description of a pocket light embodying my invention reference should now be had to the attached drawings in which:

Figure 1 is a longitudinal broken section taken on a plane through the axis of the flashlight and with the working parts shown in an "off" position;

Figure 2 is a longitudinal section of the front portion of the device illustrated in Figure 1 taken on the same plane as the section in Figure 1, but with the parts in an "on" position;

Figure 3 is a perspective view of the annular detent member;

Figure 4 is a perspective view of the release sleeve employed in connection with the member shown in Figure 3; and

Figure 5 is the bulb-carrying socket employed in the illustrated device.

The pocket light embodying my invention is preferably constructed with a tubular metal body 11, from the forward end of which projects a conventional screw base flashlight bulb 13. While I am not limited to the use thereof, I prefer the type of bulb having a lens-like portion at the tip of the bulb which focusses the light filament and projects a substantial portion of the light emitted by the bulb, in a forward direction.

In the present case the bulb 13 is screwed into a socket 14 which is slidably held inside a tubular sleeve 15 which in turn is slidably mounted in an internally shouldered opening in the front portion 113 of the body 11. The sleeve 15 is adapted to release the bulb 13 from electrical contact with a battery in a manner described in detail hereinafter. The bulb is thrust forwardly (upwardly in Figure 1) by a helical compression spring 17 threaded into the lower end of the socket 14, the forward motion of the bulb 13 being limited by an exterior shoulder 141 on the rearward end of the socket 14 which bears against the rearward end of the sleeve 15. The sleeve in turn is limited in its forward movement by an exterior shoulder 151 thereon bearing against an interior shoulder in the forward portion 113 of the body 11.

The light illustrated is powered by one or several conventional "pen-light" cells 12, against the forward end of which, compression spring 17

is anchored. A second compression spring 19 at the rearward end of the body 11 supports the rearward end of the battery or batteries 12 thrusting them forwardly against the pressure of the forward compression spring 17. Thus it will be seen that the battery or batteries 12 are resiliently supported in the interior of the tubular body 11 and are free to move somewhat in either longitudinal direction.

As has been previously stated the forward center terminal 121 of the battery 12 is employed as one of two switch points of a make-break switch for making and breaking the circuit from the battery through the bulb 13. To operate the switch so-formed the bulb 13 is pressed inwardly toward the battery 12, the socket 14 sliding therewith and compressing the spring 17. As will be seen in Figure 2 the rearward motion of the bulb 13 brings its center base terminal 131 into electrical contact with the center terminal 121 of the battery 12. Thus, the electrical circuit to the bulb 13 is completed, passing in the conventional manner through the base of the battery into the compression spring 19 thence to a screw plug 21 threadedly engaged with internal threads 112 in the body 11, thence through body 11, sleeve 15, and/or a detent 16 to be described, and socket 14 back to the bulb. As the center terminals of the bulb and battery 131 and 121 respectively make contact the battery 12 is moved rearwardly against the urging of the compression spring 19. Thus the electrical contact between the bulb and battery is maintained under a considerable degree of spring pressure.

It is obviously desirable that the bulb 13, having been pressed into the "on" position, be automatically held in this position until it is desired to extinguish the light. For this purpose an annular detent member 16, having instruck tongues 161 formed therein, is snapped into an interior annular recess 111 formed in the body 11. As can be seen in Figures 1 and 2, the detent member 16 must be compressed to a diameter equal to or less than the rear opening of the body 11 in order to assemble it into the interior recess 111. To this end the detent 16 is constructed of resilient metal such as, for example, phosphor bronze, and slit along one side as indicated by the numeral 162 in Figure 3. The width of the slot 162 is sufficient so that when it is entirely closed by compressing the detent 16, the diameter thereof is sufficiently small to enter through the rear of the body 11. The detent 16 is assembled in place by compressing it, introducing it through the rear of the body 11, sliding it forwardly, and allowing it to expand into the annular recess 111.

As can be most clearly seen in Figures 1 and 2 the detent 16 is so assembled in the body 11 that the inwardly struck tongues 161 formed therein project rearwardly. When the bulb 13 and socket 14 carried therewith are pressed rearwardly into the position shown in Figure 2, the tongues 161, because of their resilient nature, snap inwardly behind the shoulder 141 on the rear edge of the socket 14 thus preventing it from sliding forward under the urging of compression spring 17 and 19 after the external pressure on the bulb 13 has been released.

When it is desired to extinguish the light, the sleeve 15 is pressed inwardly, whereupon its rearward edge is wedged between the tongues 161 and socket 14 releasing the former from their engagement with the shoulder 141 and allowing the socket to move forward due to the pressure of

spring 17 thus breaking contact between the bulb 13 and the battery 12.

It is to be noted that the sleeve 15 may, if desired, be constructed from a non-conducting material such as a transparent or translucent plastic. If such a material is used for the sleeve 15, the electric circuit finds its return path through the body 11, the detent 16, and thence through the socket 14 as before.

If it is desired to light the light momentarily and to have it extinguish upon the release of pressure, such pressure is applied to the sleeve 15 which thus being forced rearwardly carries the socket 14 therewith by virtue of the engagement of the rearward edge of the sleeve with the shoulder 141 on the socket 14. This arrangement is of particular convenience since a finger applied to the edge of the sleeve 15 does not obscure light emanating from the bulb 13.

If it is desired to carry the light in a pocket, provision is made in the rear plug 21 for mounting a pocket retaining clip 20 clamped thereto when the plug is screwed into the threads 112. It is to be noted that sufficient depth of the threads 112 and an annular relief 114 is provided so that, if desired, the retaining clip 20 may be removed and a plug 21 screwed down tight against the rearward edge of the body 11.

While the device illustrated herein is adapted for the use of two battery cells 12, it is to be noted that only one part, namely, the tubular body 11, needs to be changed in its longitudinal dimension to adapt the light for the use of only one cell 12. Single cell pen-lights while having a shorter battery life than those with two cells, are nevertheless, because of the reduced dimensions, more convenient to carry in a handbag, pocket, etc.

One of the advantages of the device illustrated herein is that it is adaptable for use of any of the various types of battery cells of standard dimensions. That is, it is unnecessary that there be an annular metal cap at the forward end of the battery cell as provided in some makes of batteries although such a cap in no way interferes with the operation of the present device. Furthermore, it is unnecessary to remove the cardboard covering or modify the cell in any other way in order to adapt it for use in this light.

It will be appreciated by those familiar with practices in quantity manufacture, that the device illustrated herein is particularly adapted for mass production since it requires no riveting, spot-welding, soldering, or similar attaching operations in the assembly thereof. The only threaded securing member is the rear cap 21, which also serves to provide access for replacement of batteries.

While the device illustrated and described herein is fully capable of attaining the objects and providing the advantages hereinbefore stated, it is capable of considerable modification within the spirit of the invention. Therefore, I do not mean to be limited to the form shown and described herein but rather to the scope of the appended claims.

I claim:

1. In a flashlight of the class described the combination of: a tubular body adapted to receive a battery having an end terminal therein; a light bulb having a base terminal and positioned to normally project from said body; a tubular socket for said bulb supported in said body for longitudinal sliding motion therein whereby said bulb terminal selectively makes or breaks electrical contact with said battery

terminal; a spring anchored against the terminal end of said battery, adapted and positioned to urge said socket away from said battery; a detent mounted in said body adjacent said socket and adapted to engage and hold said socket against the urging of said spring to maintain said electrical contact; and a release member slidably supported in said body surrounding a portion of said bulb and movable independently of said socket to disengage said detent from said socket to allow the latter to move under the urging of said spring and break said electric contact.

2. In a flashlight of the class described the combination of: a tubular body adapted to receive a battery having an end terminal therein; a light bulb having a base terminal and positioned to normally project from said body; an internally threaded socket supporting said bulb, having an external shoulder thereon, and being supported in said body for longitudinal sliding motion therein whereby said bulb terminal selectively makes or breaks electrical contact to complete or break an electrical circuit through said bulb; a helical compression spring engaged with the threads of said socket and adapted to urge said socket and bulb carried thereby out of said contact; a detent mounted in said body and adapted to engage said shoulder and hold said socket against the urging of said spring whereby to maintain said contact; and a release member slidably supported in said body surrounding a portion of said bulb and adapted to disengage said detent from said socket whereby to allow the same to move under the urging of said spring and break said circuit.

3. In a flashlight of the class described the combination of: a tubular body adapted to receive a battery having an end terminal therein; a light bulb having a base terminal and positioned to normally project from said body; an internally threaded socket supporting said bulb, having an external shoulder thereon, and being supported in said body for longitudinal sliding motion therein whereby said bulb terminal selectively makes or breaks an electrical contact to complete or break an electrical circuit through said bulb; a helical compression spring engaged with the threads of said socket and adapted to urge said socket and bulb carried thereby out of said contact; an internal shoulder formed in said body adapted to limit said spring urged motion of said bulb; a detent mounted in said body and adapted to engage said external shoulder and hold said socket against the urging of said spring whereby to maintain said electrical contact; and a release member slidably supported in said body surrounding a portion of said bulb and adapted to disengage said detent from said socket whereby to allow the same to move under the urging of said spring and break said circuit.

4. In a flashlight of the class described the combination of: a tubular body adapted to receive a battery having an end terminal herein; a light bulb having a base terminal and positioned to normally project from said body; an internally threaded socket supporting said bulb, having an external shoulder thereon, and being supported in said body for longitudinal sliding motion therein whereby said bulb terminal selectively makes or breaks an electrical contact to complete or break an electrical circuit through said bulb; a helical compression spring engaged with the threads of said socket and adapted to urge said socket and bulb carried thereby out of

said contact; an annular detent member mounted in an interior recess in said body adjacent the terminal end of said battery, said detent member having inwardly struck tongues formed therein adapted to engage said shoulder and hold said socket against the urging of said spring whereby to maintain said electrical contact; and a release member slidably supported in said body, surrounding a portion of said bulb, and adapted to disengage said tongues from said shoulder whereby to allow said socket to move under the urging of said spring and break said circuit.

5. Switching means for a light bulb which includes: an axially slideable socket adapted to receive a light bulb; a fixed terminal adjacent said socket adapted to make electrical contact with a bulb held in said socket when the latter is moved axially inwardly to a closed circuit position; a fixed detent adapted to engage said socket and hold the same in said closed circuit position; a spring operatively associated with said socket and adapted to urge the same out of said closed circuit position; and a manually operable member mounted adjacent said socket for inward motion independent of said socket to disengage said detent from said socket and permit the same to move out of said closed circuit position.

6. In a flashlight of the class described the combination of: a tubular body having an internal shoulder in the forward end thereof; a battery having a forward end terminal mounted in said body for resiliently constrained longitudinal motion therein; a sleeve having a medial external shoulder thereon, said sleeve being slidably positioned in the forward end of said body, projecting therefrom and with said external shoulder normally seated against said internal shoulder; a bulb-receiving socket having an external shoulder formed on the rear end thereof, said socket being slidably supported within said sleeve and with said external shoulder on said socket normally seated against the rear edge of said sleeve; a compression spring threadedly engaged with said socket and anchored against the forward end of said battery whereby to urge said socket and sleeve into said normal positions thereof; a flashlight bulb mounted in said socket and having a base terminal normally spaced from said battery terminal, said bulb normally positioned to project from said body whereby said bulb is adapted to be forced rearwardly carrying said socket therewith and effecting electrical contact of said bulb and battery terminals; and an annular detent fixedly mounted in said body having rearwardly extending instruck tongues formed therein adapted and positioned to engage said socket shoulder and hold said bulb in said contact with said battery, said tongue being further adapted to be disengaged from said socket shoulder by rearward motion of said sleeve.

7. In a flashlight of the class described, the combination of: a tubular housing adapted to receive a battery therein; a light bulb receiving socket mounted for inward and outward longitudinal sliding motion in said housing adjacent an end thereof whereby to carry a light bulb in said socket selectively into or out of electrical contact with said battery; spring means interposed between said battery and socket and adapted to normally urge said socket outwardly; catch means mounted in said housing, positioned and adapted to engage said socket when the same has been moved inwardly to effect said battery contact, said catch means being further adapted to main-

tain said contact against the urging of said spring means; and a release member independently and slidably mounted in said housing positioned and adapted to be manually moved against said catch means to disengage the latter from said socket whereby to permit said spring means to move said socket outwardly.

8. In a flashlight of the class described, the combination of: a tubular housing adapted to receive a battery therein; a light bulb; a support for said bulb adapted to hold the same with a light producing portion thereof projecting beyond said housing, said support being slidably mounted adjacent an end of said housing for longitudinal motion therein selectively inwardly to make electrical contact between said bulb and battery or outwardly to break said contact; a spring anchored in said housing and urging said support outwardly; a detent fixed in said housing positioned and adapted to engage said support and hold the same in said inward position; and a member in said housing adjacent said detent adapted for motion independent of said support and projecting from said housing whereby manual operation of said member is effective to move said detent means and release the same, permitting said spring to urge said support outwardly to break said contact.

9. In light bulb supporting and switching means of the class described, the combination of: 30

a tubular body; means movably mounted adjacent an end of said body to support a projecting light bulb for limited motion to complete or break an electrical circuit therethrough; holding means associated with said body adapted to engage and hold said support means in a circuit completing position; resilient means operatively connected between said body and said support means to urge the latter out of said circuit completing position and a separately movable release member mounted in said body and having a portion thereof projecting beyond said body for manual operation to disengage said holding means from said support means to break said circuit.
